UNITED STATES PATENT OFFICE.

JOHN PAULAUSKI, OF CICERO, ILLINOIS.

AIRSHIP.

1,307,414.

Specification of Letters Patent. Patented June 24, 1919.

Application filed October 31, 1918. Serial No. 260,490.

To all whom it may concern:

Be it known that I, JOHN PAULAUSKI, a citizen of the United States, residing at Cicero, in the county of Cook and State of Illinois, have invented new and useful Improvements in Airships, of which the following is a specification.

This invention relates to air-craft designed more particularly for warfare, and 10 and its object is to provide a novel and improved driving and controlling means, this object being attained by a combination and arrangement of parts to be hereinafter described and claimed.

15 In order that the invention may be better understood, reference is had to the accompanying drawings forming a part of this specification, and in said drawings,

Figure 1 is an elevation of an air-ship 20 constructed in accordance with the present invention;

Fig. 2 is a medial cross-section of the same;

Fig. 3 is a central longitudinal section;

25 Fig. 4 is a perspective view of a rudder assembly;

Fig. 5 is a perspective view of an elevating plane;

Fig. 6 is a detail in perspective showing 30 the closure of an observation tower and gun house, and

Fig. 7 is a perspective view showing an engine support.

Fig. 8 is an elevation of the airship showing a modification; and

Fig. 9 is a cross-section of the same, taken on the line 9—9 of Fig. 8.

Referring specifically to the drawings, 10 denotes the body of the craft, the same being a metal shell, and having a cylindrical shape, with its ends tapered. The bottom of the shell is formed with a compartment 11 for the crew, machinery and supplies, and the top of the shell is formed with a gas-tight compartment 11^a adapted to be filled 45 with hydrogen or other gas to assist in sustaining the craft in the air.

At the forward end of the compartment 11 is located an engine 12 for driving the 50 main propeller 12^a. The front end of this engine is pivoted, as shown at 13, to a base 13^a, the pivotal axis being horizontal and extending transversely of the craft so that the engine may be tilted, and as the propeller moves bodily with the engine, the propeller may be set at the proper inclination

for ascending or descending. When going straight ahead, the engine will be set to bring the propeller axis horizontal.

Any suitable mechanism may be provided 60 for swinging the engine 12 for the purpose stated. Fig. 3 shows a worm gearing 14 carried by the base 13^a, and operating a pinion 15 which is in mesh with a curved rack 15^a on the engine.

An auxiliary propeller 16 is also located 65 on each side of the craft near its forward end. Each of these propellers is driven by an engine 16^a. Similar propellers are located near the rear end of the craft. The 70 engines 16^a stand out from the sides of the craft to give the propellers 16 a free working area.

As shown in Fig. 7, each pair of engines 16^a is slidably mounted on the branches 17 75 of a fork, the two forks being connected by a single shank 18 supported intermediate its ends in a bearing structure 19 suitably fixed to the bottom of the shell 10. The shank 18 is adapted to be rocked to tilt the 80 forks and thus tilt the engines so that their propellers may be set at an inclination in the same manner and for the same purpose as the main propeller 12^a. This tilting of the engines is effected by a worm wheel 20 85 on the shank 18 with which meshes a manually or otherwise actuated worm 20^a supported by the bearing member 19.

If repairs are necessary, the engines 16^a may be retracted or drawn into the body 90 10 through suitably sealed openings 23 in the latter, this being done by non-traveling screws 21 threaded through the base castings of the engines and provided with hand wheels 22.

At the top of the body 10 is an observation and machine gun tower 24 having openings 25 for aim in various directions. This tower has a normally closed top 26, but as aiming at a high angle necessitates removal 100 of the top, supporting guide rods 27, standing outward from the tower, are provided, onto which the top may be slid. The top 26 has a depending annular flange 28 which seats with a tight fit inside the tower. This 105 flange is shaped to produce an encircling external groove in which the rods 27 seat and thus serve to hold the top in place thereon when it is removed from the tower, as shown in Fig. 6.

At the center of the body 10 is held suspended a basket 29 for supporting machine-

95

110

gun men, said basket being provided with a suitable lowering tackle 30, so that it may be lowered to relieve the craft of the jar or concussion, and also to enable the 5 machine gun men to have a clear view of the enemy craft.

The craft is also provided on each side with fore and aft elevating planes 31 and 32, respectively. Each plane is carried by 10 a medial rock shaft 32^a entering the shell 10 through a frame plate 33 mounted on the latter, and to the rock shaft is fixed a hand lever 35 for operating the same to tilt the plane at the desired angle. The frame plate 15 33 carries a toothed sector 34 engageable by a spring latch on the hand lever for locking the same.

The front and rear edges of the plane have inwardly extending rods 36 passing 20 through arcuate slots 37 in the shell 10 and similar slots 38 in the frame plate 33. Each rod carries a pinion 39 which is in mesh with a curved rack 39^a on the plate 33. Adjacent to each pinion 39 is a spring bolt 25 40 which normally impedes movement of the pinion and locks the same against travel over the rack 39^a. The bolt may be withdrawn by a lever 41 carried by the lever 35 and acting on a pull wire 42. Thus, 30 when the lever 35, with both levers 41, are gripped, a release of the plane is at once effected, and the shaft 32^a may then be rocked to set the plane at the desired angle.

35 At the rear end of the body 10 are rudders 43 for changing the direction of the craft laterally, the same being pivoted at 44 and having a connection 45 to swing together. Horizontal rudders 46 are also 40 provided. Both sets of rudders are carried by rails 47 extending rearward from the body 10.

45 Entrance to the compartment 11 is had through a rear door 48, and the compartment is provided with windows through sealed tubes 49.

The wheels 50 for supporting the craft on the ground are of conventional design, and a detailed description thereof is not 50 necessary.

In the modification of Figs. 8 and 9, the

use of a single engine 16^b for each pair of propellers 16 is shown. The engine is located centrally of the airship body, and power therefrom is transmitted to the propellers 16 through a shaft 51 and bevel gears 52, supported by a suitable hanger 53. The latter also has a downward extension 54, whereby a pontoon 55 may be suspended, several of these serving to float 60 the airship when it descends upon a body of water.

While the craft is of particular advantage for aerial warfare, it should serve efficiently for mail service or transportation of 65 passengers.

I claim:

1. In an aerial craft, side propellers, engines driving said propellers, and supports for the engines on which the latter are slidably mounted, the engines and their propellers being located on the outside of the craft, and the engines being slidable on the supports into and out of the craft. 70

2. In an aerial craft, side propellers, engines driving said propellers, supports for the engines on which the latter are slidably mounted, the engines and their propellers being located on the outside of the craft, the engines being slidable on the supports into and out of the craft, and non-traveling screws having connection with the engines for effecting such sliding movement. 75 80

3. In an aerial craft, side propellers, engines driving said propellers, rockable supports on which the engines are slidably mounted, the engines and their propellers being located on the outside of the craft, and the engines being slidable on the supports into and out of the craft, the support 85 extending transversely of the craft, and means for rocking the supports. 90

4. In an aerial craft side propellers driven in pairs from an engine located within the craft, hangers projecting from the sides of the latter for the support of the propellers, and pontoons suspended from the hangers for floating the craft when on a body of water. 95

In testimony whereof I affix my signature. 100

JOHN PAULAUSKI.
